CLAIM

The ornamental design for a tablet stand, as shown and described.

DESCRIPTION

FIG. 1 is a front perspective view of a tablet stand;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a front perspective view showing a tablet being used with the tablet stand.

The broken lines shown in the drawings depict environmental structure that forms no part of the claimed design.
